UNITED STATES PATENT OFFICE

LEO F. HEERWAGEN, OF FAYETTEVILLE, ARKANSAS

AWNINGS

Application filed May 20, 1930. Serial No. 454,058.

This invention relates to new and useful improvements in awnings, and has more particular reference to an end curtain for awnings.

5 A prime object of this invention is to provide for use in conjunction with that type of roll awning used for shading display windows, an end curtain for the awning.

Other objects and advantages of the present invention will become apparent during a study of the following description, taken in connection with the present invention wherein:

15 Figure 1 is a side elevational view of a roll type store awning having my improved end curtain associated therewith.

Fig. 2 is a detail sectional view taken substantially on the line 2—2 of Fig. 1.

20 Fig. 3 is a side elevational view of my improved end curtain, the same being shown in a partially rolled condition.

25 Fig. 4 is a longitudinal sectional view taken through the roller supporting brackets, the rollers being shown with parts broken away.

30 Fig. 5 is a detail sectional view taken through the device as shown in Fig. 3 for more clearly illustrating the manner of supporting the roller supporting bracket.

35 With reference more in detail to the drawings, it will be seen that I have designated generally by the reference character 5, a conventional type of awning, known in the art as a roll awning, and that type of awning now used generally in conjunction with store display windows.

40 As is well known in the art, due to the fact that when awnings are in a raised or partially rolled condition the end curtains sag downwardly, as to be a constant nuisance to passers-by, the end curtain often sagging low enough as to knock off one's hat passing under the awning, with the result that one 45 would often walk out of range of the awning, rather than to chance the possibility of being so annoyed.

45 Of course, in this way, prospective shop 50ers instead of being attracted toward the display window were rather repelled because

of such possible annoyances as above referred to.

The common practice now, is to provide such roll awnings without end curtains, with the result that it is practically impossible for 55 the awning to protect the window from the sun as it should.

It is therefore in the provision of a side curtain for rolled awnings, which will overcome the difficulties above referred to, that this invention is concerned.

60 Thus, it will be seen that I have provided a novel form of end curtain for use with the awning 5.

According to the present invention, there 65 is provided an end curtain for each end of the awning. Each of the end curtains comprises a substantially triangular supporting web or curtain section 6 having one edge thereof secured to the wall of the building, 70 vertically in close proximity to the end of the awning 5.

The said edge of the curtain section 6 may be secured in any well known manner. At its opposite edge, the curtain section 6 is 75 folded upon itself and stitched as at 7 to provide a pocket 8 extending for the full length of the curtain section. Supported in the pocket 8 is a roller carrying bracket. The roller carrying bracket comprises a pair of 80 sections 9 and 10 respectively. The sections 9 and 10 are each formed from an elongated strap, one end of the straps being arranged in overlapping relation while at their free ends the straps are bent inwardly in parallel 85 co-extensive relation as at 11 and 12 respectively.

The overlapping ends of the sections 9 and 10 are adjustably secured together through 90 the medium of a bolt and slot connection designated generally by the reference character 13. The adjustability of the bracket permits of the use of any desired length spring roller designated generally by the reference character 14.

95 The roller 14 has its end pintles journaled in suitable openings formed in the end extensions 11 and 12 of the bracket sections. Suitably secured to the end 12 of the bracket section 10 is an inverted U-shaped pivot 100

bracket 15, the legs of which are suitably apertured as at 16 for receiving the ends of a pivot bolt as at 17 on the outer end of a bracket 18 suitably mounted beneath the lower end of the curtain section 6.

5 Completing the end curtain, is a curtain section 19, which may be of course, canvas or any other suitable material conforming in color to the awning 5. The curtain section 19 is substantially triangular and has the lower edge thereof suitably scalloped or otherwise formed as is conventional with the edge of ordinary awnings.

10 The curtain 19 at its widest end is suitably secured to the roller 14 and said curtain 19 is windable on the roller 14. At its forward or smallest end at the upper corner thereof, the curtain 19 is provided with a suitable opening 20 for receiving one end of the forward or weight rod R of the awning 5.

15 Thus it is obvious that the end curtain 19 will be operated simultaneously with the operation of the awning 5 for winding and unwinding the end curtain 19 upon its roller 14.

20 25 It will be also noted that when the awning 5 is being rolled up, as when not in use, tension being released on the roller 14 the same will be rotated under the action of its spring 14' in a manner well known in the art for 30 winding the curtain 19 thereon.

35 As the awning 5 nears the completion of its rolling operation, the rod R will strike against the upper pintle of the roller 14, thus swinging the bracket supporting the roller 14 upon its pivot 17 for moving the bracket inwardly toward the wall of the building so that when it has been rolled up, the awning with my improved end curtain associated therewith will present a neat and pleasing 40 appearance.

45 An advantage of an end curtain of this character, is that the awning 5 may be rolled for any predetermined extent, that is to say, may be rolled as to be only partially extended. Likewise, the end curtain 19 will only be unwound in proportion to the unwinding of the awning 5 so that obviously there will be no sagging or bagging of the end curtain 19 when the awning is in a partially rolled or unrolled condition, it being apparent that the curtain 19 will also be in a partially unrolled or rolled condition.

50 Even though I have herein shown and described the preferred embodiment of my invention, it is to be understood that the same is susceptible to changes fully comprehended by the spirit of the invention as herein described, and the scope of the appended claims.

55 60 Having thus described my invention, what I claim as new is:

1. In an awning, a separable end curtain therefor, a roller on which said end curtain is windable, means for pivotally supporting said roller for swinging movement on a ver-

tical plane adjacent the end of the awning, means for limiting the swinging movement of said roller, said end curtain at its forward free end provided with an opening for receiving one end of the forward weight rod of the awning.

2. An end curtain for awnings, separable from the awning, and comprising a substantially triangular shaped curtain section adapted to be secured at one edge thereof to a suitable support for disposition adjacent the end of the awning, a second curtain section, a roller upon which said second curtain section is windable, means for rotatably mounting said roller on said first-mentioned curtain section, and means for retaining said curtain section under tension when partially or entirely unwound.

3. An end curtain for roll awnings comprising a substantially triangular curtain section adapted to be secured at one end to a support adjacent the end of the awning, said curtain section having a pocket extending lengthwise thereof, a longitudinally adjustable roller supporting bracket arranged in said pocket, means for pivotally connecting one end of said bracket to the support beneath the lower end of the first-mentioned curtain section, a substantially elongated triangular curtain section, a roller for said second-mentioned curtain section carried by said roller supporting bracket, said roller being of the spring type, and said second mentioned curtain section at its smallest end provided with means for engagement with the awning whereby said second-mentioned curtain will be wound and unwound from said roller upon the rolling and unrolling of said awning.

4. An end curtain for awnings comprising a substantially triangular curtain section adapted to be secured to the support of the awning adjacent one end of the awning, a longitudinally adjustable bracket, means for supporting said bracket on said curtain section, a roller journaled in said bracket, a second curtain section windable on said roller, said second mentioned curtain section adapted to have one end thereof operatively connected with the awning whereby said curtain section will be wound and unwound from said roller during extending or contracting of the awning proper, and a relatively fixed member disposed in longitudinal alignment with the first mentioned curtain section, and means pivotally connecting one end of said bracket with said fixed member.

5. In combination, an awning, an end curtain therefor, said end curtain comprising a curtain section adapted to have one edge thereof secured to the support of the awning adjacent one end of the awning, and a self contracting curtain section carried by the first mentioned curtain section and co-

operating with said first mentioned curtain section to provide an end curtain of a length substantially equal to the transverse width of the awning.

5 6. An awning comprising in combination an end curtain including a bracket, means for pivotally mounting said bracket, said means including means for limiting swinging movement of said bracket, and a self contracting curtain section carried by said bracket and adapted to be expanded and contracted during expansion and contraction of the awning.

In testimony whereof I affix my signature.

LEO F. HEERWAGEN.
